MANIFOLDING DEVICE

Arthur Hediger, Zurich, Switzerland

Application May 13, 1942, Serial No. 442,828

14 Claims. (Cl. 282—3)

The invention relates to a new and improved manifolding device and more particularly to manifolding devices adapted to be used in book-keeping making use of loose sheets for the ledger and the accounts. The invention relates still more particularly to devices of said type adapted to be used for writing entries by hand on a customer's account sheet, such entries being transferred by means of carbon sheet or other transferring sheets on to a journal or ledger sheet. Devices of this type are known in which forms with identical divisions or columns such as debit date, debit text, debit sum columns are used for the account sheets and the journal sheets in such a manner that entries and figures entered in the columns of the account sheet will be transferred on to the said journal sheet in like columns.

The main object of the invention is to improve the devices of the type aforesaid by the provision of means to prepare automatically a group register sheet or balancing sheet on which the debits and credits are tabulated in groups, facilitating the making out of the balance sheet. While writing the entries on the customer's accounts sheet, the entries and figures are not only transferred to the journal sheet but also on to the group register sheet, having as many group columns as are necessary for balancing books. The account sheets as well as the journal sheets are each provided with a column in which the group number is inserted. A hand operated locator is used to place the said group register sheet on each entry in such a position that the figures written on the account sheet appear in the proper column of the group register sheet. All the items and figures written on the account sheet and journal sheet appear sorted out and tabulated in the proper columns on the group register sheet.

In the accompanying drawings is shown an example of construction of the subject of the invention.

Fig. 1 shows a perspective view of the device.

Figs. 2 to 4 are sections on the lines II—II, III—III and IV—IV, respectively, of Fig. 1 to a larger scale.

Fig. 5 is a longitudinal section through a slide forming a part of the device.

Fig. 6 shows a part of the slide from underneath.

Figs. 7 and 8 are sections on the line VII—VII of Fig. 5 with the separate parts in different positions.

Fig. 9 shows a part of the device in perspective and partly broken away.

Fig. 10 shows a considerably enlarged section on the line X—X of Fig. 1.

Fig. 11 shows to a smaller scale a section on the line XI—XI of Fig. 1 with the writing plate raised.

The device has a base plate 1 the longitudinal edges of which are provided with bars 3, 4. The bars 3, 4 are provided with grooves in which a slide 2 is mounted. Over the bars 3, 4 lie two plates 5, 6 which are both pivotally arranged on the bar 4. The plate 5, which is a writing plate, is provided with a slot 7 in which is located a rail 8. The latter is secured at the top and bottom to the bars 3, 4. A rail 9 is rigidly secured to the writing plate 5 and a clamping rail 10 (Figs. 1, 3, 4) is hinged to the said plate. The rail can be rocked by means of hand grips 11. On the clamping rail 10 is pivotally mounted a clamping rail 12 provided with hand grips 13. The supporting plate 6 carries a clamp 14 for accounts R, and a holder 15 for pens and pencils. To the bar 4 is connected a holder 16 for stamps. The bar 4 also carries two carriers 17, 18 (Figs. 1, 2) in which a supply roll 19 of copying paper is rotatably mounted. In the carrier 18 (Fig. 1) and in a further carrier 21 is rotatably mounted a second supply roll 20 of copying paper. To the writing plate 5 are also hinged two holding rails 22, 23 (Fig. 2), of which the former lies on the upper and the latter on the lower side of the plate 5.

At the lower end of the base plate 1 is provided a fixed foot bar 24 (Fig. 2) and at the upper end is a rockable foot bar 25. The latter is wider than the bar 24, the plates receive an inclination which facilitates writing. A turn-button or jamb 26 releasably holds the foot bar 25 in the position shown in Fig. 2.

The right hand side of the slide 2 is provided with a gripping bar 30 (Figs. 1, 3, 5, 6), in which six rods 32, each provided with a knob 31, are mounted parallel to one another and axially movable. Each of the rods 32 is provided with a notch 33 (Fig. 5) into which projects a lug 34 of a numeral plate 35 located above the slide 2.

Over the plate 35 is arranged a cover plate 38 provided with windows 37. Each plate 35 bears the same number twice, the numbers of each pair being side by side but different from one another for example by their colour. One or the other of the numbers (in the present example 1-6) of the plates 35 appears in the window when one of the rods 32 is moved. Each rod 32 is connected at its free end to a ratchet bar 40 (Figs. 5, 6) subjected to the action of a spring 42. All the

ratchet bars 40 are slidably mounted in a casing 41. Each ratchet bar 40 is provided with an inclined bearing surface 43 and two stops 44, 45 the purpose of which is described hereinafter. In the casing 41 there is also a spring actuated locking pawl 46 and with each ratchet bar 40 there is associated a rockable locking member 50 subjected to the action of springs 48, 49. The locking members 50 are provided with slots 51, with which projections 52 (Fig. 3) can engage. The latter are secured at regular intervals under the slide 2 to the base plate 1. Springs 49 on the locking members 50 frictionally engage the slanting surfaces 43 of the ratchet bars 40 while the locking pawl 46, Fig. 5, is adapted for holding engagement against the shoulders 44, 45 of the ratchet bars 40 to hold said bars against the action of the spring 42. Upon forward movement to the left, Fig. 5, of any rod 32 and ratchet bar 40, the locking pawl 46 will swing into holding engagement against the shoulder 45 of the advanced bar 40, while its relation to the other bars 40 remains as shown in Fig. 5.

On the underside of the slide 2, two shafts 61, 62 are mounted in bearings (Figs. 5, 6) of which each carries three clamping members 63. Springs 65 tend to press the ends 63' of the clamping members 63 against the slide 2. One clamping member 63 of each shaft 61, 62 is provided with an extension 66 (Fig. 3) on which is seated a pin 67 projecting through the slide 2.

The clamp rail 10 firmly holds the journal sheet J, the clamp rail 12 the account sheet K, the clamp members 63 the group register sheet G and the clamp 14 for example the account R to be entered.

The device enables one of the group columns 1 to 6 of a group register sheet G to be adjusted selectively relatively to the numeral column Z (i. e. the account number, debit and credit columns calculated together) of the journal sheet J and of the account sheets K, so that by single writing down there is obtained an entry not only on the account sheet K and the journal sheet J, but simultaneously also the necessary entries in one of the group columns 1 to 6 of the group register sheet G. For this purpose the sheet G lies on the slide 2, on which it is held firmly by the clamping members 63 subjected to the action of the springs 65. By pressure on a pin 67 the ends 63' of the clamping members 63 are raised and the group register sheet G can be removed or exchanged. As will be seen from Figs. 3, 9 and 10, the sheet G lies not only on the slide 2 but is passed over the rail 8 which lies in the slot 1 of the writing plate 5. The width of the rail 8 corresponds exactly with that of the numeral column Z and the numeral column both of the journal sheet J and of the account sheet K lies exactly on the rail 8. At each time of writing down the number is thus entered on the account sheet, on the journal sheet and on the group register sheet G, and the figure in the debit and credit.

Before inserting the group register sheet G, the plates 5, 6 are swung upwardly (Fig. 11). The group register sheet G is placed over the freely exposed slide 2 and over the rail 8 and clamped firmly as above described. The plates 5, 6 are then again lowered. The copying paper 20' of which the width corresponds with that of the rail 8, is withdrawn from the roll 20 and placed over the group register sheet G, rail 8 and the lower edge of the writing plate 5. Thereupon the copying paper 19' which corresponds in width

with the width of the journal sheet, is unwound from the spool 19 and placed over the writing plate 5. That surface of the paper 20' which furnishes the copying ink impression is directed downward while the corresponding ink surface of the paper 19' is directed upwardly. On the latter is placed the journal sheet J, consisting of transparent paper, and it is slid under the clamping bar 10, so that it is held immovably. The clamping bars 22, 23 serve for holding the lower and upper edges of the copying papers 19', 20'. To the clamping bar 23 there is preferably secured a protecting strip 28 (Fig. 2) bent in the form of a U, which surrounds the lower edge of the plate 5. This protecting strip 28 may be replaced or even combined with a device which enables the fully used copying paper, which can no longer be used, to be cut off. It is also possible to combine with the protecting strip a device enabling the copying paper to be drawn along by a half line spacing so as to enable the copying paper to be used completely.

Near the upper edge of the slide 2 are provided two angle pieces 29 (Figs. 1, 9) which serve as stops for the group register sheet G. The two angle pieces 29 are movable within predetermined limits so as to equalize irregularities in the head width of the sheet G, so that the latter can always be firmly clamped in alignment with the journal sheet J.

Hereinafter for the purposes of explanation it will be assumed for example that an entry is to be made on the goods account sheet, which bears the group number 4. After having read from the rail 12 on which line of the journal sheet J an entry is to be made, the account sheet K is so moved under the slightly raised clamping bar 12 that the lines of the sheets J and K to be written upon are superimposed. By releasing the hand-piece 13, the sheet K is firmly clamped. The vertical columns of all the forms M, J and G thus lie exactly one above another (see Fig. 1). In order that the entry to be made on the group register sheet G will also take place in the column appertaining to the group 4, the slide 2 must be moved to such an extent that the group 4 of the sheet G lies on the rail 8. For this purpose the button 31 associated with the number 4 is pressed. The rod 32 is thus moved axially and there is effected a movement of the numeral plate 35. In the opening 37 there appears the second previously covered number 4 which in the manner already described is provided in a distinctive manner for example in red colour. When moving the rod 32 against the action of the spring 42 the ratchet bar 40 is also moved until the pawl 46 engages with the stop 45 and thus holds the ratchet bar 40 firmly. During this operation the inclined bearing surface 43 has rocked the spring 49 and therewith the locking member 50 from the position in Fig. 7 into the position shown in Fig. 8 (in chain dotted lines in Fig. 5). In the new position of the locking member 50 a stop 52 projects into its path. If now the slide 2 is moved, one stop 52 snaps, at a predetermined moment, into the slot 51 of the rocked locking member 50, subjected to the action of the spring 48 and holds the slide 2 firmly in the position in which the group 4 of the group register sheet G lies on the rail 8.

When writing on the account sheet of group 4 there is effected in the known manner also the same entry on the journal sheet J. At the same time there are now effected in a novel manner also in the group 4 of the group register sheet G the

entries made in the number column Z. There is therefore obviated the hitherto tedious operation of writing separately on the sheet G, where by a source of error is excluded completely. When account sheets of other groups are to be written upon the hand-piece 31, corresponding with the number of the group of the account sheet in question, is pressed and the slide 2, when moved, is so held firmly, by the corresponding locking member 50 and a stop 52, that the desired group 10 of the sheet G always lies on the rail 8 for being written upon. With each group-number is associated a set of parts 31-35, 40, 42, 48-52, whilst the pawl 46 is common to all the slides. 15 When a ratchet bar 40 is locked by the pawl 46, it is released, in that when the knob 31 of another rod 32 and its ratchet bar 40 is moved and the pawl 46 is raised from the stop 45. On the return of the released ratchet bar 40, into its normal position (Figs. 5, 6), the locking member 50 associated therewith also rocks into its earlier position over the stop 52. As will be seen from Figs. 2 and 3 the stops 52 are spaced predetermined distances apart.

The balance can be obtained at any time from 25 the group register sheet. As in each sheet G the group-number is also located in each group column adjacent the debit and credit amount, it is extremely simple to see whether each amount stands in the correct group column.

The indicating device 35-37 could also be arranged on one of the bars 3, 4. Instead of separate journal sheets it is also possible to use a band movable over the writing plate, capable of being fixed by the clamping bar 10 and wound on, 35 a supply spool.

The new device may for example be built up, together with a flat typewriter. In this case the typewriter may be provided with an adding device which adds the written amounts.

In the example shown, there has been shown a group register sheet with six group or number columns Z. The slide 2 may, however, be made wider so that, for example, there is room for twelve groups. The guide grooves in the bars 3, 4 for the slide are extended so that the slide 2 can be drawn out not only towards the right (Fig. 1) but also towards the left. At the left hand edge of the slide are provided rods and numbers as above described for the right hand edge. Further there are provided entirely similarly constructed and similarly operating locking elements 40-52.

In particular cases it may be desirable to write the business transactions or the numerical items, written underneath one another on the journal sheet J, in a horizontal line on the group register sheet G. In order to obtain this result the parts, which firmly hold the journal sheets and the account sheet, may be made vertically movable relatively to the parts which firmly hold the group register sheet.

It is frequently desirable to use the apparatus also for booking accounts. In this case the separate items should each be written as the debit and credit side of a form. The arrangement could be such that the slide 2 can always be moved by the amount of the width of a debit column or a credit column, whilst an indicating device is provided which indicates the column, debit or credit, in which the entry is made.

What I claim is:

1. In a manifolding device of the character described, the combination of a writing plate, a rail between the longitudinal edges of said writ-

ing plate and separated from the body of the plate by longitudinal slots, means for independently clamping sheets of tabulated paper to said writing plate with predetermined columns thereon in registry, a slide plate movable transversely of the writing plate underneath the same, means for clamping a tabulated sheet of paper to said slide plate in such position that a portion of said sheet overlies said rail, means for holding copying paper between tabulated sheets positioned on said writing plate and slide, and means for holding said slide with respect to the plate in a position in which a selected column of the slide sheet overlies the rail, whereby an entry made in the top sheet on the plate will be copied into the corresponding column of another plate sheet, and the selected column of the slide sheet.

2. A manifolding device of the character described, comprising in combination, a stationary writing plate, means for independently clamping sheets of tabulated paper to said writing plate with predetermined columns thereon in registry, a rail between the longitudinal edges of said writing plate and separated from the body of the plate by longitudinal slots, a slide plate movable transversely of the writing plate and of the rail underneath the same, means for clamping a tabulated sheet of paper in predetermined position to said slide, and threading said paper through the slots between the rail and the plate, means for holding copying paper between tabulated sheets positioned on said plate and slide, means for locking said slide with respect to the plate in a position in which a selected column of the slide sheet overlies the rail while the remainder of said slide sheet is in a plane beneath said rail and plate, whereby an entry made in the top sheet on the plate will be copied into the corresponding column of another plate sheet and the selected column of the slide sheet.

3. A manifolding device of the character described, comprising a bed frame, a writing plate provided with a slot hinged along one edge to the bed frame, a rail fixedly secured to the bed frame in a position to occupy the slot in the writing plate when the latter is in operative position, a slide plate movable transversely of the writing plate underneath the same and underneath said rail, means for clamping a tabulated sheet of paper in predetermined position to said slide with a portion of said paper on the slide overlying said rail when the latter has been exposed through upward swinging movement of the writing plate, means for independently clamping sheets of tabulated paper to said writing plate with predetermined columns of said plate sheets in registry above the rail, means for holding copying paper between the tabulated sheets positioned on said plate and slide, and means for locking said slide with respect to the plate in a position in which a selected column of the slide sheet overlies the rail, whereby an entry made in the top sheet on the plate will be copied into the corresponding column of another plate sheet, and the selected column of the slide sheet.

4. In a manifolding device of the character described, the combination of a bed frame, a writing plate provided with a slot and hinged along one longitudinal edge to said frame, a rail secured to said frame at a location between the edges of said slot when the writing plate is in operative position on the frame, the top face of said rail being flush with the top of said writing plate when the latter is in operative position, means for independently clamping sheets of tabulated

paper to said writing plate with predetermined columns on said sheets in registry above the rail when the writing plate is in operative position, a slide plate movable transversely of the writing plate underneath the same and underneath said rail, means for clamping a tabulated sheet of paper in predetermined position on said slide plate when the writing plate is swung away from the bed frame to maintain said sheet of paper on the sliding plate above the rail on the bed frame and beneath the writing plate when the latter is returned to operative position, means for holding copying paper between tabulated sheets positioned on said plate and slide, and means for locking said slide with respect to the plate and rail in a position in which a selected column of the slide sheet overlies the rail, whereby an entry made in the top sheet on the plate in a column overlying the rail will be copied into the corresponding column of another sheet clamped to the plate and into the selected column of the slide sheet.

5. In a manifolding device of the character described, the combination of a bed frame, a writing plate having a slot pivotally secured to said bed frame along one edge thereof, a rail fixedly secured to the bed frame at a position in which said rail is located in the slot of the writing plate when the latter is in operative position, the top face of the rail and the top face of the writing plate being coplanar when the writing plate is in operative position on the frame, clamping means secured to the writing plate and movable with the same with respect to the bed frame for independently clamping sheets of tabulated paper to said writing plate with predetermined columns of said sheets in registry above said rail upon movement of said writing plate and sheets to operative position with respect to the frame, a slide plate movable in the frame in a direction parallel to the pivotal axis of the writing plate, means for clamping a tabulated sheet to said slide with a portion of said sheet overlying said rail, and the remainder of said sheet beneath said writing plate when the latter is moved to operative position, stops fixed to the frame, and holding means secured to the slide plate, said holding means being adapted for cooperation with the stops to retain the sliding plate in a position in which a column selected on the sliding plate is in registry with the rail, and means for holding copying paper between tabulated sheets positioned on said plate and slide, whereby an entry made in the top sheet on the writing plate will be copied into the corresponding column of another sheet on said writing plate and into the selected column of the sheet on the slide.

6. In a manifolding device of the character described, the combination of a bed frame, a writing plate having a sectionalized body movably secured to the bed frame, a rail fixedly secured to the bed frame between sections of said writing plate and separated from the same by slots when the writing plate is in operative position on the bed frame, means for independently clamping sheets of tabulated paper to the writing plate with predetermined columns thereon in registry above said rail, a slide plate movable with respect to the writing plate, means for clamping a tabulated sheet of paper to said slide plate with a portion of said sheet overlying said rail, means for locking said slide with respect to the writing plate in a position in which a selected column of the slide sheet overlies the rail, means for holding a sheet of ordinary paper of the width of the rail in

registry with the rail above the tabulated sheet secured to the slide, means for holding other copying paper on the writing plate in position to effect entries on one of the sheets secured to the writing plate, whereby an entry made in the top sheet on the writing plate will be copied into the corresponding column of another sheet secured to the writing plate, and into the selected column of the tabulated sheet on the slide.

7. In a manifolding device of the character described, the combination of a bed frame, means for holding tabulated sheets in selected relation to each other and in predetermined position with respect to the frame, a slide plate guided in a rectilinear path on the frame, means for clamping another tabulated sheet on said slide plate, cooperating holding means on said frame and said slide plate for locking said slide plate with respect to said frame in a position in which selected columns on the tabulated sheet clamped to the slide plate occupy a predetermined relation with respect to selected columns on the sheets clamped in fixed relation to the frame, and means for indicating on the slide plate the columns of the tabulated sheet on the slide plate, said indicating means being operatively connected with said locking means on the slide plate for holding the slide plate with respect to the frame in a position in which said selected columns of the slide plate sheet are operative with respect to the columns on the frame sheets.

8. In a manifolding device of the character described, the combination of a bed frame, a slide plate guided in a rectilinear path on said bed frame, means for clamping a tabulated sheet in predetermined position on the slide plate, and means for selectively locking said slide plate to present selected columns of the sheet clamped thereon in predetermined position with respect to said frame, the frame having holding means cooperated with the locking means on the slide plate, and the slide plate having manipulating means for selectively moving any of the locking means thereon to operative relation with respect to the holding means on the frame.

9. In a manifolding device of the character described, the combination of a bed frame, a slide plate guided thereon in a rectilinear path, clamping means for securing a tabulated sheet having a plurality of columns in predetermined position on said slide plate, locking means on said slide plate in a number corresponding to the number of columns on the tabulating sheet, holding means on the frame, each of said holding means being adapted for cooperation with a different one of said locking means of the slide plate, indicating means on the slide plate, and means for simultaneously operating said indicating means and locking means on the slide plate to maintain upon movement of the slide plate with respect to said frame, a selected column on the tabulated sheet, as indicated by the indicating means in a predetermined position with respect to the bed frame upon displacement of the slide with respect to the bed frame.

10. In a manifolding device of the character described, the combination of a bed frame, a slide plate guided thereon in a rectilinear path, means for clamping a tabulated sheet having a plurality of juxtaposed columns in predetermined position on said slide plate, cooperating elements on said slide plate and on said bed frame for retaining the slide plate with respect to said bed frame in a position in which a selected column on the tabulated sheet occupies a

predetermined position with respect to the bed frame, indicating means on the slide, and means for selectively operating said locking means on the slide and said indicating means on the slide to retain the slide in a position in which the column of the tabulated sheet indicated by the indicating means occupies a predetermined position with respect to the bed frame.

11. In a manifolding device of the character described, the combination of a bed frame, a slide guided for rectilinear movement in said bed frame, means for clamping a sheet having a plurality of tabulating columns juxtaposed thereon in predetermined position on said slide, a plurality of ratchet bars supported by said slide and movable relatively thereto, locking elements carried by said slide and actuatable by said ratchet bars, holding elements on the bed frame adapted for cooperation with the locking elements carried by said slide, and means on the slide for selectively displacing said ratchet bars with respect to said slide to bring the locking elements on the ratchet bar operated by the manipulating means to operative position with respect to the holding element on the frame, whereby the tabulated sheet clamped to the slide presents a column selected by the operation of said manipulating means in a predetermined position with respect to the frame.

12. In a manifolding device of the character described, the combination of a bed frame, a slide guided in a rectilinear path on said frame, means for clamping a tabulated sheet having a plurality of columns juxtaposed thereon in predetermined position to said slide, locking elements on said slide, holding elements on the bed frame, means on the slide for selectively manipulating one of the locking elements for cooperation with the holding element on the frame, whereby a selected column on the sheet clamped to the slide plate is presented in a predetermined position with respect to the bed frame, and means for retaining said locking and holding elements in operative position upon release of the manipulating element secured to the slide.

13. In a manifolding device of the character described, the combination of a bed frame, a slide guided in a rectilinear path on said bed

frame, means for clamping a tabulated sheet having a plurality of columns in juxtaposition thereon in predetermined position on said slide, indicating means for the columns on said tabulated sheet mounted on said slide in such position as to be normally inaccessible to observation, locking elements on said slide corresponding in number to the number of columns on said tabulated sheet, holding elements corresponding in number to the number of columns on the tabulated sheet and secured to the bed frame, and means selectively operable on the slide for moving the indicating means corresponding to said manipulating means to a position accessible for observation and for moving the locking means on the slide corresponding to the selected column on the tabulated sheet into position for cooperation with the holding elements on the frame, whereby upon movement of the slide relatively to the frame, a selected column of the tabulated sheet on the slide is retained in predetermined position with respect to the frame.

14. In a manifolding device of the character described, the combination of a bed frame, a slide guided for movement in a rectilinear path thereon, means for clamping a tabulated sheet having a plurality of juxtaposed columns in predetermined position on said slide, a ratchet element movably supported by said slide, a locking element actuated by said ratchet element when the latter is moved relatively to the slide, holding elements on the bed frame adapted for cooperation with the actuated locking elements of the slide to retain the slide against further movement, the number of the ratchets, locking elements and holding elements respectively corresponding in number to the number of the columns on the tabulated sheet, a plurality of selectively operable manipulating means for the ratchets, means for holding the ratchets in predetermined position with respect to the slide, said ratchet holding means being operable upon actuation of any of the ratchet bars to release position with respect to the previously actuated ratchet bar and to holding position with respect to the other ratchet bars.

ARTHUR HEDIGER.
